US00D894385S

(12) **United States Design Patent** (10) **Patent No.:** **US D894,385 S**
Giordano et al. (45) **Date of Patent:** **** Aug. 25, 2020**

(54) **ORTHOPEDIC TOOL**

(71) Applicant: **OrthoPediatrics Corp.**, Warsaw, IN (US)

(72) Inventors: **Michael Giordano**, Osceola, IN (US); **Chris Powers**, Burkett, IN (US)

(73) Assignee: **OrthoPediatrics Corp.**, Warsaw, IN (US)

(**) Term: **15 Years**

(21) Appl. No.: **29/623,904**

(22) Filed: **Oct. 27, 2017**

(51) LOC (12) Cl. **24-02**

(52) U.S. Cl.

(57) **CLAIM**

The ornamental design for an orthopedic tool, as shown and described.

DESCRIPTION

FIG. 1 is a rear, top, right side perspective view of a first embodiment of an orthopedic tool showing our new design; FIG. 2 is a front, bottom, right side perspective view thereof; FIG. 3 is a rear side view thereof;

FIG. 4 is a right side elevation view thereof;

FIG. 5 is an enlarged top plan view thereof;

FIG. 6 is a front elevation view thereof.

FIG. 7 is a left side elevation view thereof; and

FIG. 8 is an enlarged bottom plan view thereof.

FIG. 9 is a rear, top, right side perspective view of a second embodiment of an orthopedic tool showing our new design. FIG. 10 is a front, bottom, right side perspective view thereof;

FIG. 11 is a rear side elevation view thereof;

FIG. 12 is a right side elevation view thereof;

FIG. 13 is an enlarged top plan view thereof;

FIG. 14 is a front elevation view thereof.

FIG. 15 is a left side elevation view thereof; and,

FIG. 16 is an enlarged bottom plan view thereof.

The broken lines depict portions of the orthopedic tool that form no part of the claimed design.

1 Claim, 12 Drawing Sheets
